DISPLAY CARD

William H. Weil, Richmond Hill, N. Y., assignor to
Stransky Products Corporation, New York,
N. Y., a corporation of New York

Application May 29, 1939, Serial No. 276,311

3 Claims. (Cl. 206—79)

The present invention relates to improvements over the device disclosed in Patent No. 2,009,422, dated July 30, 1935, which discloses a display card wherein there may be mounted supporting attachments or the like for pictures, cards, etc., for displaying them.

An object of the present invention is to provide means whereby such attachments or picture suspending devices may be held in display position on the card by so mounting the same that portions thereof are adapted to exert pressure upon other corresponding portions, so that the established pressure of each attachment or suspending device upon each other provides reliable means for securely holding a set or group of the attachments in display position.

Another object of the invention is to provide simple means for mounting such an attachment on the card, by one simple movement of the hand or other medium, thereby rendering the mounting more expeditious, this act of mounting deflecting certain portions of the card so that thereupon the attachment is positioned in display position.

Further objects are to provide simple, efficient and reliable means for securely mounting such attachments or suspending devices for display on a card.

These being among the objects of the present invention, the same consists of certain features of construction and combinations of parts to be hereinafter described and then claimed, reference being had to the accompanying drawing illustrating a suitable embodiment of the invention and wherein

Fig. 1 is a broken plan of one of the card blanks;

Fig. 2 is a broken plan of a card showing how the attachments or suspending devices are mounted thereon for display;

Fig. 3 is an enlarged broken plan showing more clearly how one of the attachments cooperates with an adjacent one;

Fig. 4 is an enlarged broken plan showing the back of the portion of the card shown in Fig. 3;

Fig. 5 is a section on the line 5—5, Fig. 3, viewed in the direction of the arrows;

Fig. 6 is a section on the line 6—6, Fig. 3, viewed in the direction of the arrows;

Fig. 7 is a section on the line 7—7, Fig. 3, viewed in the direction of the arrows;

Fig. 8 is a broken plan of a portion of the card showing the position which one of the attachments may take when in the act of mounting it on the card;

Fig. 9 is a section on the line 9—9, Fig. 8, viewed in the direction of the arrows; and

Fig. 10 is a broken plan of a card blank showing a slight modification thereof.

Referring to the drawing, preferably the card

10 is of suitable flexible cardboard adapted to be slotted through, although it will be obvious herefrom that the invention is not necessarily restricted thereto. The articles or devices 11 to be supported on the card 10, preferably are the well known picture suspending attachments, such as disclosed by the aforesaid patent. Each of such picture hanging devices includes a pronged base cross-piece 12, a narrower apertured member or eye 13 for receiving a supporting nail and a neck 14 connecting the cross-piece and the member 13.

The card 10 has elongated supporting members 15, preferably formed as strips cut out from the card. These elongated supporting members or strips extend parallel with each other and are arranged in stepped relation in the entire set or group thereof. Each member 15 or strip is defined by slits, comprising a long slit 16, shorter end slits 17, 18, preferably substantially at right angles to slit 16, and a slit 19, preferably substantially parallel with slit 16, which defines the outer longitudinal edge of the member 15, while slit 19 defines the inner edge thereof. Each slit 19 is of such a length as to extend for a substantially greater distance than the width of the neck 14 of the article, as more clearly shown in Figs. 3 and 4.

At the ends of each elongated member or strip 15, bendable connections 20, 21 are formed laterally of each member, the connection 21 being defined by the slit 18 and the adjoining terminal of the slit 19 while the bendable connection 20 is defined by the slit 17 and by a slit 22 at the opposite terminal of slit 19. Each pair of meeting slits 19, 22 define a flap 23.

It will be noted that each flap 23 will therefore have two merging edges defined by the slits 19, 22, they meeting in a corner 24, and one of said edges being opposite the adjoining edge of the supporting member 15, and the other edge of the flap which is defined by the slit 22 extends away from the adjoining edge of the supporting member and the corresponding edge of the flap. The edge of the flap which is defined by the slit 22 is formed by commencing said slit 22 at a point located at the left hand end of the adjoining edge of the supporting member 15, and by deflecting the slit 22 slightly outwardly away from the corner of the flap 23 and terminating the slit 22 preferably at a distance away from slit 19 which is approximately the length of slit 19. Preferably the slit 22 is curved outwardly and then inwardly towards its outer terminal. Hence

each flap 23 will have two edges of substantially equal length and the corners or merging points 24 of the edges of all of the flaps will extend in substantially the same direction.

While the shape of the flap 23 is shown as preferred, nevertheless the slit 23 could even be

shorter than shown, say about one-half of its length, and be even straight, and if straight it may extend at right angles to the slit 19 or it may be inclined somewhat outwardly away from the slit 19.

Referring to Figs. 2 and 3 it will be noted that each displayed article has two main portions of relatively different widths, the wider portion or cross-piece 12 being held under and by each supporting member 15, and the narrower portion or eye 13 projecting over each flap 23. The reason why the article to be displayed can be inserted into display position is that the distance between the outer edge of the supporting member connection 20, which is nearest to or directly adjacent to the edge of the flap defined by the slit 22, and the remote end of the adjoining edge of supporting member 15, defined by slit 19, is slightly greater in length than the width of the narrow portion or eye 13. These proportions enable the narrower main portion 13 to be pushed underneath the supporting member 15 and onto the flap 23, and the insertion may be made by inclining the article as shown in Figs. 8 and 9 and by pushing the article inward so as to finally position the portion or eye 13 over the flap, and then adjusting and squaring up the position of the article to that shown in Figs. 2 and 3. On the other hand, the article may be pushed straight in to position it, but in either case the same is shifted to the right to move the portion or eye 13 fully over onto the flap 23. The positioning of the article may therefore be accomplished by one movement, and the only parts hidden will be those directly adjacent the neck 14 of the article and the neck.

Referring again to Figs. 2 and 3 it will be noted that when a plurality of articles are in a displayed position and the set of them arranged in a slanting position, as shown in Fig. 2, that portions of all but one of the articles bear in succession on corresponding ends of the strips or supporting members 15 next adjacent to them, pressing said ends inwardly at 25 upon the articles extending under the said next adjacent strips or members 15. Of course such pressure also reacts in the opposite direction, and all of the articles will eventually be retained in position by upward pressure from beneath. Preferably by using the card 10 slotted, as shown, the last article to be inserted is the one to the extreme left.

Again referring to each flap 23 which has but two merging edges it will be noted that it is connected with the card along a line inclined to the supporting member 15, which line passes through the outer terminal of the slit 22 and through the remote end of the adjoining edge of the supporting member 15, so that when the eye or narrower main portion 13 of the article is first brought into engagement with the flap, the flap and the surrounding portion of the card can move relatively to each other.

A slight modification of the card 10 is shown in Fig. 10 wherein the slits 26 which define one edge of each flap 27 are at the right hand ends of the supporting members 28. Obviously this construction of card enables the articles to be positioned in a similar manner to what is shown in the remaining figures of the drawing.

It will be obvious to those skilled in the art that other changes are within the spirit of the invention and the scope of the appended claims.

What I claim as new is—

1. A display card having an elongated supporting member laterally connected at its ends there-

with and underneath which an article may be mounted on the card, the card having a relatively movable flap with only two merging edges and over which a part of the article may extend, one 5 of said edges located directly opposite the adjoining inner edge of the supporting member and between the end connections, and the other edge extending away from said adjoining inner edge and starting from the point of emergence of both 10 edges at one end of said adjoining edge, said other edge deflected slightly outwardly away from its starting point and deflected inwardly and then terminating, the length of said inner edge of the supporting member being somewhat less than the 15 other edge thereof and corresponding to the distance between the end-connections and to the length of said one edge of the flap, and the flap connected with the card along a line inclined to the supporting member and which passes through 20 the outer terminal of its said other edge and through the remote end of the adjoining edge of the supporting member.

2. A display card and article assembly, the card having an elongated supporting member connected at its ends therewith and a relatively movable flap with only two merging edges, one of 25 said edges located directly opposite the adjoining inner edge of the supporting member and between the end connections, and the other edge extending away from said adjoining inner edge and starting from the point of emergence of both edges at one end of said adjoining edge, said other edge terminating at its outer end at a distance away from said one edge, and the displayed article 30 having two main portions of relatively different widths and a connecting neck therefor, the wider portion held under and by said supporting member, and the narrower portion projecting over said flap, from between the adjoining opposite 35 edges of the supporting member and the flap, the distance between the outer edge of the supporting member connection directly adjacent to said other edge of the flap and the remote end of said adjoining edge being slightly greater than the 40 width of said narrow portion of the article, and said article being insertable into display position by passing said narrower portion underneath the supporting member and engaging it over and onto the face of said flap and moving the article to an 45 adjusted display position.

3. The combination of a display card and articles mounted thereon for display, the card provided with a series of flexible strips which extend lengthwise of each other and are offset from each other edgewise, and the articles extending underneath the strips and each displayed beyond the edges of its strip, portions of all but one of the articles bearing in succession upon corresponding ends of the strips next adjacent them and pressing said ends inwardly upon the articles extending under said next adjacent strips, thereby securing all of the articles, and the card having a flexible flap next to one edge of each strip, each flap having but two edges which converge at a point adjoining the end of the strip which is opposite to the end pressed inwardly, and each flap adapted to be deflected backwardly by one end of the article when the article is being pushed under its strip to its display position, and each strip being slightly longer than the width of said one end of the article, for the distance between the inner edge of one connection and the outer edge of the other connection, to permit said one end to be pushed over the corresponding flap.

WILLIAM H. WEIL.
